UNITED STATES PATENT OFFICE.

HARRY E. ROSE, OF SPOKANE, WASHINGTON.

PROPELLING DEVICE.

1,227,200.

Specification of Letters Patent. Patented May 22, 1917.

Application filed June 17, 1916. Serial No. 104,194.

To all whom it may concern:

Be it known that I, HARRY E. ROSE, a citizen of the United States, and a resident of Spokane, in the county of Spokane and State of Washington, have invented a certain new and useful Improvement in Propelling Devices, of which the following is a specification.

My invention relates to improvements in propelling devices, more particularly to propelling devices for aeroplanes, and it consists in the combinations, constructions, and arrangements herein described and claimed.

An object of my invention is to provide a propelling device in which a plurality of movable blades or wings is so mounted that, when the blades move toward the rear of the device, a greater surface area is presented than when they move toward the front, thereby propelling the device forwardly.

A further object of my invention is to provide a device of the type described in which the blades or wings are mounted on endless chains, said blades passing through the interior of a casing in substantially folded condition and spreading out on emerging from the casing so as to present a greater surface area.

A further object of my invention is to provide a propeller of the type described which may be used for other devices, such as boats.

Other objects and advantages will appear in the following specification, and the novel features of the invention will be particularly pointed out in the appended claims.

My invention is illustrated in the accompanying drawings forming part of this application, and in which—

Figure 1 is a perspective view of an aeroplane provided with my improved propelling device.

Fig. 2 is a longitudinal sectional view through the device.

Fig. 3 is a transverse section along the line 3—3 of Fig. 2.

Fig. 4 is an enlarged sectional view through one of the wings or vanes.

Fig. 5 is a perspective view of a modified form of link for the endless chain.

Fig. 6 is a section along the line 6—6 of Fig. 4.

Referring now particularly to Figs. 1 and 2, I have shown therein a main frame 1 which supports one of the sustaining planes 55 2. This frame carries at its bottom the car 3 or basket, the engine 4, and has a rearwardly extending portion 5 beneath which is disposed the lower of the main sustaining planes 6. The usual rudder 7 is attached at 60 the rear of the device. The machine is designed to be supplied with ailerons and elevating planes, not shown.

The frame 1 supports a casing which I have denoted in general by C. As will be 65 seen from the drawings, this casing consists of an inner cylinder 8 and an outer wall 9 which is tapered but which is cylindrical in cross section. These inner and outer walls are held in spaced relation by means of radially extending partitions or brace members 10, see Fig. 3. At the ends of the device between the brace members are disposed sprocket wheels 11. It will be noted that these sprocket wheels 11 are at the larger 70 end of the device. At the other end are similar sprocket wheels 12. These sprocket wheels bear endless chains 13, like that shown in Fig. 2, or of any suitable form, as, for instance, having links like that shown in 80 Fig. 5 at 14.

Secured to each of these endless chains is a series of wings or vanes, like that shown at 15 in Fig. 4. These wings are provided with suitable brace members 16, in order to 85 withstand the wind pressure. Fig. 1 shows the preferred arrangement of these wings. From this figure it will be seen that the wings of adjacent sets are not disposed in the same plane but are slightly offset, being 90 arranged like the ribs of a fan, one slightly behind the other, so that when they are brought into folded position they will lie one behind the other. In the drawings I have shown only a few sets of wings, but 95 obviously a greater or less number may be provided, without departing from the spirit of the invention.

The endless chains are driven by the motor 4 through the medium of a sprocket 100 chain 17, and a sprocket wheel 18, see Fig. 3, on a shaft 19. This shaft 19 connects at its ends with universal joints 20 which drive the sprocket wheels 11, the axle of one wheel

being connected to the axle of its adjacent wheel by means of a universal joint 20'.

Now it will be obvious that, as the endless chains travel around the sprockets 11 and 12, the vanes or wings 15 will be carried with them. These vanes or wings are arranged so that they will enter the large end of the casing C and diverge from the small end. Owing to the shape of the casing the wings will be virtually in alinement, that is to say, behind one another, just as the ribs of a fan are behind one another when the fan is closed. The effective surface area of the line of wings which are advancing toward the small end of the casing, is, therefore, not much greater than that of one of the wings, while on emerging from the small end of the casing, the wings spread out into the form shown in Fig. 1, whereby the full surface area is available for propelling the device.

In order to reduce the back pressure due to the forward movement of the device, I provide a conical shield 21 which is carried by the frame 1, and which is spaced from the casing C just far enough to permit the exit of the wings or vanes.

The same principle might be applied to the propelling of boats or other water craft.

I claim:

1. In a propelling device a hollow cylinder, a series of wings or vanes movably mounted on said cylinder and arranged to travel from one end of the cylinder to the other on the inside thereof and back on the outside, said vanes being one behind the other when on the inside of the cylinder, and being spread out when on the outside of the cylinder.

2. A propelling device comprising a hollow cylinder, a series of endless chains carried by the cylinder, means for driving said chains, and a series of wings or vanes projecting laterally from the chains, said wings being carried by the chains out of one end of the cylinder and into the other end of the cylinder by the movement of the endless chains.

3. A propelling device comprising a hollow cylinder, a series of endless chains extending longitudinally of the cylinder, each of said endless chains having a portion inside the cylinder and a portion outside the cylinder and portions encircling the end of the cylinder, a series of wings or vanes carried by each endless chain, and means for causing the travel of the chains.

4. A propelling device for aeroplanes, comprising a hollow cylinder, a series of endless chains disposed longitudinally of the cylinder, a portion of each chain being on the inside of the cylinder and a portion on the outside, a series of wings or vanes carried by each endless chain, the wings of one chain being slightly out of alinement with

the wings of the adjacent chain on either side thereof, and means for causing the simultaneous travel of the chains.

5. In a propelling device for aeroplanes, a cylinder, a plurality of endless chains carried by the cylinder, said endless chains being disposed longitudinally with respect to the cylinder and having portions on the inside and outside of the cylinder, a series of wings or vanes carried by each of said longitudinally extending chains, the wings of one chain being out of alinement with the wings of the adjacent chains on either side thereof, and means for causing the movement of the chains from one end of the cylinder to the other at a uniform speed for all the chains.

6. In a propelling device for aeroplanes, a casing having a double wall, one of said walls being an inner cylindrical wall and the other wall being an outer tapered wall of cylindrical cross section, an endless chain disposed longitudinally of the casing and arranged to travel through the inner portion of the casing in one direction and in the opposite direction on the outside of the casing, a plurality of wings or vanes carried by said endless chain, a plurality of similar endless chains disposed in parallel arrangement with said first named endless chain around the casing, each of said endless chains having wings or vanes slightly offset from the wings or vanes of the adjacent chains, and means for driving all of said endless chains simultaneously at the same speed in the same direction.

7. In a propelling device for aeroplanes, a casing having double walls, the inner wall being cylindrical, the outer wall surrounding the inner wall and being tapered, said outer wall being cylindrical in cross section, a plurality of endless chains disposed longitudinally with respect to the casing, a portion of each chain being on the interior of the casing and a portion being on the exterior, means for moving the said chains simultaneously so as to travel toward the larger end of the outer wall on the exterior thereof, and in the opposite direction within the cylindrical interior wall, a plurality of wings or vanes carried by each of the endless chains, said wings or vanes being arranged in groups with the wings of adjacent endless chains, the wings of any one group being arranged to move one behind the other when the wings are on the inside of the casing.

8. In a propelling device for aeroplanes, a casing having double walls, the inner wall being cylindrical, the outer wall surrounding the inner wall and being tapered, said outer wall being cylindrical in cross section, a plurality of endless chains disposed longitudinally with respect to the casing, a portion of each chain being on the interior of

the casing and a portion being on the exterior, means for moving said chains simultaneously so as to travel toward the larger end of the outer wall on the exterior thereof and in the opposite direction within the cylindrical interior wall, a plurality of wings or vanes carried by each of the endless chains, said wings or vanes being arranged in groups with the wings of adjacent

endless chains, the wings of any one group 10 being arranged to move one behind the other when the wings are on the inside of the casing, and means comprising a conical wind shield disposed at one end of the casing and spaced therefrom to permit the exit of the 15 vanes or wings.

HARRY E. ROSE.
